Attorney

UNITED STATES PATENT OFFICE.

JOSEPH CHEFKO, OF NEW YORK, N. Y., ASSIGNOR TO HELEN CHEFKO, OF NEW YORK, N. Y.

GAME.

Application filed December 5, 1922. Serial No. 605,025.

To all whom it may concern:

Be it known that I, JOSEPH CHEFKO, a citizen of the United States, residing at New York, in the county of New York and State 5 of New York, have invented certain new and useful Improvements in Games, of which the following is a specification.

This invention relates generally to games, having more particular reference to games 10 that are played by moving a number of pieces over a marked board, the invention having for an object the provision of a novel game of this type, a further object relating specifically to a novel means for retaining 15 the pieces in the position to which they are adjusted.

For further comprehension of the invention, and of the objects and advantages thereof, reference will be had to the following 20 description and accompanying drawings, and to the appended claims in which the various novel features of the invention are more particularly set forth.

Fig. 1 of the drawings is a plan showing 25 a novel gameboard on which my improved game is played.

Fig. 2 is a detail axial vertical sectional view of one of the pieces, indicating it in 30 position on the gameboard.

Fig. 3 is a horizontal sectional view taken on the line 3—3 of Fig. 2.

For the playing of my game I provide a gameboard 10 of square outline and which may have a raised portion 11 which comprises the playing area. As here shown this 35 playing area is in the form of a cross, leaving depressed corner pocket portions 12 in which the pieces employed in playing the game may be placed when not in use, these 40 pockets being surrounded by walls 13 of equal height with the surface of the playing field.

The playing field is composed of two sections which represent respectively a pasture 45 and a sheep fold or stable, the portion at the top representing the fold and being surrounded at top and sides by any marking such as 16 to represent the wall of the fold, the lower side being open to the pasture. 50 Each arm of the playing field comprises a square, there being in consequence five squares in the playing field, the upper square forming the fold. Extending along the square boundaries are shallow vertical 55 grooves 18 and horizontal grooves 19, while

the different squares are further divided by the median vertical grooves 20 and horizontal grooves 21, and by the diagonal grooves 22. These grooves represent paths leading to the fold and the junction points thereof 60 represent stations at which the various pieces are located. The pieces employed are of two sorts, representing respectively foxes (or wolves) and lambs (or sheep). Of the former, indicated at F, there are only two, and of the latter indicated at L, there are twenty. The foxes are situated at stations at the corners of the fold, while the lambs are situated at the stations throughout the 65 pasture.

In playing the game I utilize pieces of the detail construction shown in Figs. 2 and 3. As there shown the piece comprises a main body 25 in the form of a disk and which is formed with an elongated interior recess 26. Carried for vertical adjustment in this disk is a pin 27 which projects downward through a suitable aperture in the bottom of the recess. The upper end of this pin is formed with a diminished neck 28 engaged by the ends of a pair of levers 29 fulcrumed between their ends as at 30 in the recess 26. The opposite ends of these levers are engaged by the lower ends of a pair of studs 31 which project upwardly through suitable apertures in the top of the disk and have a circular plate 32 fixed on their upper ends, this plate having the representation of the appropriate animal on the upper face thereof. A coiled expansion spring 33 bears downwardly on the pin 27, while flanges 34 on the studs 31 limit the upward movement thereof. The pin 27 is of oval cross sectional shape, the aperture in the disk through which it projects being of like shape, and gameboard is formed at proper points on the playing field with sockets 36 of similar shape to the pins but of slightly larger diameter. If it is desired to lock the pieces in their stations on the board, as when the players are leaving the game temporarily before the latter is finished, the pieces may be turned around until the pins assume the positions shown in dotted lines in Fig. 3 causing the pins to bind in the sockets and thus lock the pieces in place.

The object of the game is to get as many of the lambs from their stations in the field into the fold as the latter will hold. The lambs must move along the paths formed

by the grooves and if any of the lambs gets on a station adjacent a fox, with a vacant station immediately behind, the fox will pass to such station, the lamb being removed from the board. Since there are more lambs than the fold can contain it is obvious that one of the features of the game will be the sacrificing of certain of the lambs so as to lure the foxes to one side. In the event that one of the foxes fails to take a lamb which could be taken, this fox is removed and remains off the board until the other fox has captured a lamb, when it is replaced. In moving the pieces the plates 32 are depressed and the pieces moved along the grooves to the desired station, when the plate 32 is released.

The gameboard may be formed in two parts hinged together along the dotted line 40, the playing field being preferably arranged on the board so that this line will not intersect any of the stations on the latter.

Having thus described my invention what I claim as new and desire to protect by Letters Patent of the United States is as follows:

1. In combination, a gameboard formed with a series of sockets, and a playing piece comprising a hollow body, and a pin carried by said body, and adapted to engage in any of said sockets or be drawn up into the said body.

2. In combination, a gameboard formed with a series of sockets, and a playing piece having a pin movable therein and adapted to engage in any of said sockets or be drawn up into the body of the piece, and a member movably mounted above the body of the piece and operative connections between the said member and the pin adapted to cause said pin to be raised upon depression of said member.

3. In combination, a gameboard formed with a series of sockets, and a playing piece having a pin movable therein and adapted to engage in any of said sockets or be drawn up into the body of the piece, and a member movably mounted above the body of the piece, operative connections between said member and the pin adapted to cause said pin to be raised upon depression of said member, and a spring normally holding the said pin in lowered position.

4. A gamepiece comprising a disk-like body formed with a recess, a pin movable vertically in said body to be projected therebelow or be raised therein, a pair of levers fulcrumed in said body and engaging said pin to raise the latter, a pair of studs engaged with said levers and projecting upward from the said body, and a plate mounted on the upper ends of said studs.

5. A gamepiece comprising a disk-like body formed with a recess, a pin movable vertically in said body to be projected therebelow or be raised therein, a pair of levers fulcrumed in said body and engaging said pin to raise the latter, a pair of studs engaged with said levers and projecting upward from the said body, and a plate mounted on the upper ends of said studs, and an expansion spring engaged with said pin and urging the same downward.

6. In combination, a gameboard formed with a series of sockets, and a playing piece having a pin movable therein and adapted to engage in any of said sockets or be drawn up into the body of the piece, said pin being of oval cross section, and said sockets being of complementary shape whereby said pin may be frictionally locked in any of said sockets by a partial rotation of the pin.

In testimony whereof I have affixed my signature.

JOSEPH CHEFKO.
